PAIR OF SPECTACLES

Austin B. Belgard, Evanston, Ill.

Application July 13, 1953, Serial No. 25,924

Term of patent 14 years

(Cl. D57—1)

To all whom it may concern:

Be it known that I, Austin B. Belgard, a citizen of the United States, residing at Evanston, county of Cook, and State of Illinois, have invented a new, original, and ornamental Design for a Pair of Spectacles, of which the following is a specification, reference being had to the accompanying drawing forming a part thereof, in which:

Fig. 1 is a top plan view of a pair of spectacles, showing my new design;

Fig. 2 is a front elevational view thereof;

Fig. 3 is a bottom plan view thereof, shown partially broken away for purpose of convenience;

Fig. 4 is a side elevational view thereof; and

Fig. 5 is a fragmentary cross-sectional view thereof taken on the line 4—4 of Fig. 2 on an enlarged scale.

The characteristic feature of my design resides in the gusset-like webs located above and below the temple-attaching end pieces of the spectacle front.

I claim:

The ornamental design for a pair of spectacles, as shown and described.
